H. QUAST

FINGER RING

Filed June 10, 1927

FIG. 1.

FIG. 2.

FIG. 3.

FIG. 4.

Herman Quast
INVENTOR
BY *Victor J. Evans*

WITNESS: *John Donoran*

ATTORNEY

UNITED STATES PATENT OFFICE.

HERMAN QUAST, OF ARLINGTON, MINNESOTA.

FINGER RING.

Application filed June 10, 1927. Serial No. 197,904.

This invention relates to jewelry and particularly to finger rings.

A general object of the invention is to provide a finger ring that can be adjusted to fit 5 various sized fingers and the adjustment means is entirely concealed from view, with the result, the adjustable feature will in no way mar the beauty of the ring.

A further object of the invention is to provide 10 an adjustable finger ring that is simple in construction, and is inexpensive to manufacture.

This invention also consists in certain other 15 features of construction and in the combination and arrangement of the several parts, to be hereinafter fully described, illustrated in the accompanying drawings and specifically pointed out in the appended claims.

In describing my invention in detail, reference 20 will be had to the accompanying drawings wherein like characters denote like or corresponding parts throughout the several views, and in which:

Figure 1 is a side elevation of a ring constructed 25 in accordance with my invention.

Figure 2 is an edge elevation thereof.

Figure 3 is a sectional view taken on line 30 3—3 of Figure 2.

Figure 4 is a sectional view taken on line 4—4 of Figure 3.

Referring to the drawings in detail, the reference numeral 1 indicates the shank of the ring which of course is curved upon itself in ring formation and terminates in threaded 35 end portions 2. The mounting which in the present instance is shown as being of the gypsy basket type, is indicated by the reference numeral 3 and includes the usual depending hollow arm 4 within which are secured spaced parallel apertured ears 5, adapted to receive the threaded end portions 2 of the shank 1 in the manner as best shown in Figure 3 of the drawings. Disposed between each set of ears 5 and threadedly receiving 40 the threaded end portions 2 of the shank 1 is a nut 6 which is mounted for rotation and it will be obvious that upon rotating the nut 6 the diameter of the shank will be varied as the threaded end portions will be caused to travel toward or away from the mounting 3, it depending of course upon which way the nut is rotated.

The nut is of substantially disk formation

and is provided in its periphery with semi-circular recesses 7 so that a pin may be inserted through openings 8 formed in the sides of the mounting for engagement in said recesses for rotating the nuts as will be apparent.

While I have shown a gypsy basket type 60 mounting, it will be obvious that other types of mountings may be used without departing from the spirit of the invention.

From the above description and disclosure of the drawings, it will be obvious that the 65 ring may be readily adjusted to fit various sized fingers by merely inserting a pin or other like element through openings 8 formed in the sides of the mounting and rotating the nuts as above set forth, and by this novel construction, the ring may be applied to the finger and adjusted thereon.

It is thought from the foregoing description that the advantages and novel features of my invention will be readily apparent. 75

I desire it to be understood that I may make changes in the construction and in the combination and arrangement of the several parts, provided that such changes fall within the scope of the appended claims. 80

What I claim is:

1. A ring of the character described comprising a shank disposed in ring formation and having threaded ends, a mounting formed with openings in its sides, ears arranged in pairs and disposed upon opposite sides of said mounting adjacent said openings, a nut mounted between each pair of ears and being adapted to receive the threaded ends of said shank and said nuts being provided with recesses in their periphery to receive an implement passed through the side openings to rotate said nuts for adjusting the shank with respect to said mounting. 85

2. A ring of the character described comprising a curved shank having threaded ends, a mounting, ears formed with said mounting and being disposed in pairs on the opposite inner sides thereof, nuts receiving the threaded ends of said shank whereby the 90 diameter thereof can be varied and said nuts being arranged between the ears of each pair for engagement therewith. 100

In testimony whereof I affix my signature.

HERMAN QUAST.
